UNITED STATES PATENT OFFICE.

ANDREW M. MCGILL AND LUCIEN B. HOWLAND, OF TORONTO, ONTARIO, CANADA.

POWER ATTACHMENT FOR MOTOR-CARS.

1,156,418.

Specification of Letters Patent.

Patented Oct. 12, 1915.

Application filed February 8, 1915. Serial No. 6,968.

To all whom it may concern:

Be it known that we, ANDREW MELVILLE MCGILL and LUCIEN BARNES HOWLAND, both subjects of the King of Great Britain, and residents of the city of Toronto, county of York, Province of Ontario, in the Dominion of Canada, have invented certain new and useful Improvements in Power Attachments for Motor-Cars, described in the following specification and illustrated in the accompanying drawings, that form part of the same.

The principal object of this invention is to enable the owners of motor cars to utilize same for the application of power for purposes other than the propulsion of the vehicle thereby turning the machine to useful advantage in effecting a saving in time and labor and often allowing otherwise impossible tasks to be accomplished.

A further object is to devise an attachment which will not interfere with the ordinary operation and use of the car, may be readily removed and replaced if desired, and which may be made at very low cost.

The principal feature of the invention consists in the novel construction and arrangement of parts, whereby an extension shaft is supported at the front of the machine and connected to the engine shaft, and whereby a current of air is directed toward the engine radiator to cool same and allow of extended running.

In the drawings, Figure 1 is a longitudinal mid-sectional elevational view of the device showing the frame of the motor car in section and the shaft attachment to the engine shaft. Fig. 2 is a top plan view. Fig. 3 is a perspective view showing the device attached to a car.

Like numerals of reference indicate corresponding parts in each figure.

Referring to the drawings, 1 and 2 are the transverse front end members of the motor car frame.

3 is a bracket of substantially V-shape adapted to be secured to the front end of the motor car having the lug ends 4 secured by the bolts 5. The sides 6 of the bracket 3 are preferably formed of a rigid angle section and extend forwardly and downwardly to the front end 7 upon which the journal bearing 8 is supported. The upper flanges of the sides 6 have formed integrally therewith a web 9 which extends inwardly and rearwardly to the lugs 10 which

are secured to the lower front bar 2 of the car.

11 is a bar extending between the lugs 10 and dropped downwardly to form a pocket 60 in which a journal bearing 12 is secured, said bearing being arranged in horizontal alinement with the bearing 8 and both of these bearings are arranged in alinement with the engine shaft 13, and the bearing 65 14 which ordinarily supports the starter crank shaft.

15 is a socket member removably secured to the front end of the engine shaft and having a squared socket 16 formed in the 70 forward end.

17 is the extension shaft journaled in the bearings 8 and 12 and having a squared end 18 fitting in the socket 16.

19 is a suitable starter crank arranged on 75 the outer end of the shaft 17.

20 is a pulley keyed to the end of the shaft 17 extending beyond the bearing 8 having the spokes 21 thereof forming the blades of a fan which are adapted to drive 80 a current of air inwardly toward the front of the car.

22 are apron shaped plates secured to or forming part with the bracket 3 and extending downwardly and forwardly in a 85 sloping direction into close proximity with the fan. These aprons are adapted to direct the current of air from the lower half of the fan upwardly in the direction of the engine radiator.

The bracket 3 extends forwardly of the frame of the car a sufficient distance so that the pulley 20 will extend beyond the foremost portion of the front wheels of the vehicle in order that a belt connected to said 95 pulley will pass the wheels and operate without difficulty.

With a device such as described attached to a motor car the power of the engine may be utilized for various purposes while the 100 car is standing and affords a very valuable equipment for the use of farmers or others who may desire to utilize power in places and under conditions where such would not be readily obtainable. The arrangement of 105 the fan-pulley in front of the car allows of the continued utilization of the device as it creates an air circulation toward the car equivalent to ordinary running conditions when the car is in motion.

The device is of very simple, rigid and durable construction and may be manufac-

90

110

tured at very low cost and may be very quickly attached or detached as required.

What we claim as our invention is:—

1. A power attachment for motor cars, comprising, a cantaliver shaped frame rigidly secured at one end to the frame of the car and having its downwardly sloping sides converging to the outer end, a journal bearing arranged at the outer end of said frame, and a supplementary shaft detachably connected to the engine shaft and journaled in said bearing.

2. A power attachment for motor cars, comprising, an extension member adapted to be secured to the frame of the car, a supplementary shaft connected to the engine shaft and extending forwardly and journaled in said extension member, and means operatively connected to said supplementary shaft for directing a current of air toward the front of the radiator of the car.

3. A power attachment for motor cars, comprising, an extension member adapted to be secured to the frame of the car, a supplementary shaft connected to the engine shaft and extending forwardly and journaled in said extension member, and a fan attached to said supplementary shaft adapted to direct a current of air against the radiator of the car.

4. A power attachment for motor cars, comprising, an extension member adapted

to be secured to the frame of the car, a supplementary shaft connected to the engine shaft and extending forwardly and journaled in said extension member, a fan attached to said supplementary shaft, and apron extensions on said extension member adapted to direct the current of air from the lower half of the fan in an upward direction toward the radiator of the car.

5. A power attachment for motor cars, comprising, a rigid bracket member secured to the front of the frame of the car and extending forwardly therefrom having side members of rigid angle section and a depressed central web forming a supporting strut adapted to engage the car frame centrally of its width, journals supported on said bracket in alinement with the engine shaft, an auxiliary shaft detachably connected to said engine shaft and journaled in said bearings and extending beyond the forward end, and a pulley secured to the outer end of said shaft.

Signed at the city of Toronto, county of York, Ontario, Canada, this 5th day of February, 1915.

ANDREW M. MCGILL.
LUCIEN B. HOWLAND.
